CLAIM

The ornamental design for an electronic signalling transmitter for the retrieval of animals, as shown and described.

DESCRIPTION

FIG. 1 is a front view of the electronic signalling transmitter for the retrieval of animals showing my new design; FIG. 2 is a back view of the electronic signalling transmitter for the retrieval of animals shown in FIG. 1; FIG. 3 is a right-side view of the electronic signalling transmitter for the retrieval of animals shown in FIG. 1, with the lid portion shown in open condition; FIG. 4 is a left-side view of the electronic signalling transmitter for the retrieval of animals shown in FIG. 1; FIG. 5 is a bottom view of the electronic signalling transmitter for the retrieval of animals shown in FIG. 1; and, FIG. 6 is a top view of the electronic signalling transmitter for the retrieval of animals shown in FIG. 1.
